Primary Examiner—Philip S. Hyder*Assistant Examiner*—C. Tuttle*Attorney, Agent, or Firm*—William E. Hein**[57] CLAIM**

The ornamental design for a tool for precision haircutting, as shown and described.

DESCRIPTION

FIG. 1 is a front perspective view of a tool for precision haircutting, showing my new design;

FIG. 2 is a front elevation view, the rear elevation view being a mirror image thereof;

FIG. 3 is a top plan view; and,

FIG. 4 is a left side elevation view, the right side elevation view being identical thereto.

The undisclosed bottom edge of the spine forms no part of the claimed design.
